JOHN G. ROGERS, OF DOWAGIAC, MICHIGAN.

Letters Patent No. 195,255, dated July 12, 1870.

IMPROVEMENT IN PRUNING-SHEARS.

The Schedule referred to in these Letters Patent and making part of the same.

I, JOHN G. ROGERS, of Dowagiac, in the county of Cass and State of Michigan, have invented certain Improvements in Pruning-Shears, of which the following is a specification.

The nature of my invention relates to that class of pruning-shears having a saw combined; and

The improvement consists in a more convenient and simple arrangement of the several parts.

The accompanying drawing shows a longitudinal view through the diameter of the handle A. This handle must be sufficiently long to reach the limbs to be pruned.

In one end of this handle the shank of the shear-blade B is permanently fixed.

The other shear-blade, C, is provided with the slot D, which allows of a longitudinal movement of this blade as the shears are opened and shut.

The shank of blade C is curved, as seen at E, and impinges on the shoulder, F, on the shank of blade B.

To the curved shank E is attached one end of the connection-rod G.

The other end of this rod is pivoted to the short lever H.

The stationary end of lever H is pivoted to the handle A.

It will now be seen that any movement of the short lever H will cause, through the action of the slot D, pin L, and shoulder F, a combined lateral and longitudinal movement of the blade C, being a movement most desirable in pruning-shears.

To the lower end of handle A is pivoted the saw J, having the spring K, which acts on the saw similar to the action of the spring of a pocket-knife on its blade, holding the saw in position, whether extended for operation or folded into the handle, where it is entirely out of the way when using the shears.

Having thus fully described my invention, What I claim is—

The shears, consisting of the blade C, with curved shank E, slot D, rod G, and lever H, and the blade B, shank, with pin L, shoulder F, and handle A, with saw J and spring K, constructed and arranged as described.

JOHN G. ROGERS.
